Inventor George Westinghouse Jr.
By Attorney George H. Christ.

UNITED STATES PATENT OFFICE.

GEORGE WESTINGHOUSE, JR., OF PITTSBURG, PENNSYLVANIA.

PRESSURE-REGULATOR AND CUT-OFF.

SPECIFICATION forming part of Letters Patent No. 341,295, dated May 4, 1886.

Application filed March 12, 1886. Serial No. 195,117. (No model.)

To all whom it may concern:

Be it known that I, GEORGE WESTINGHOUSE, Jr., residing at Pittsburg, in the county of Allegheny and State of Pennsylvania, a citizen of the United States, have invented or discovered a certain new and useful Improvement in Pressure-Regulators and Cut-Offs, of which improvement the following is a specification.

In the accompanying drawings, which make part of this specification, Figure 1 is a vertical central section, at the line *xx* of Fig. 2, through a pressure-regulator and cut-off embodying my invention; Fig. 2, a horizontal section at the line *yy* of Fig. 1; Fig. 3, a vertical central section, on an enlarged scale, through the casing of the by-pass valve, and Fig. 4 a face view of the delivery check-plug detached.

My present invention relates to fluid-pressure regulators of the general type illustrated in Letters Patent of the United States Nos. 312,543 and 324,905, granted and issued to me under date of February 17, 1885, and August 25, 1885, respectively; and its object is to provide an apparatus which may be conveniently connected in the line of the supply-pipe, and which, in the event of a material reduction of the volume of supply, will effect a desired proportionate reduction of delivery-pressure and will regulate variations of the same within determined limits before wholly cutting off the supply.

The improvements claimed consist in certain novel devices and combinations herein-after fully set forth.

In the practice of my invention I provide, as in my Letters Patent Nos. 312,543 and 324,905 aforesaid, a pair of regulating and cut-off valves mounted in a casing, and a pressure-chamber communicating therewith and fitted with a weighted diaphragm, which is coupled to the stem of the valves and actuates the same under variations of supply-pressure to maintain a uniform rate of delivery-pressure, or to entirely cut off the supply should the pressure thereof be reduced below that which will support combustion at the burners.

In my Letters Patent above referred to the pressure-chamber is exterior to the line of traverse of fluid from the supply to the delivery pipes, and is supplied with fluid through

one or more openings leading out of the main channel of supply, and the constructions are further of such character as to cut off the supply entirely when its pressure has been materially reduced without providing for supply and regulation at pressures considerably below the maximum average.

Under my present invention I provide for the direct traverse of the entire volume of supplied fluid through the pressure-chamber, so that the apparatus may be interposed between two sections of a supply-line and form part thereof, and further render regulation practicable for an average minimum pressure substantially less than, say, one-half of an average maximum pressure.

The regulating and cut-off valve casing 1 is connected at one end by bolts 10 to a flange on the outer end of a supply nozzle or passage, 23, on one side of the pressure-chamber 2, and is provided at its opposite end with a coupling-piece, 21, or a flanged nozzle, for the connection of the supply-pipe. A delivery nozzle or passage, 22, leads out of the opposite side of the pressure-chamber, and a coupling-section, 25, of any suitable and preferred construction, connected to its outer end, provides for the attachment of a pipe through which fluid at regulated pressure is delivered to the required points of consumption. A double-beat regulating and cut-off valve, 34, composed of two disks of substantially equal diameters, is secured upon a stem, 36, the disks of the valve being adapted to seat on opposite sides, respectively, of a partition, 35, extending across the valve-chest 1, and being located at such distance apart upon their stem as to permit, when both are raised equally from their seats, the passage of the maximum quantity of fluid required to be supplied to the delivery-pipe. The stem 36 passes freely, so as to have the capacity of longitudinal movement, through a central guide or socket in a delivery check plug or partition, 45, extending across the inner end of the valve-casing 1, and having a series of openings or passages, 46, the combined area of which is sufficient to admit of the delivery of the desired maximum quantity of fluid to the pressure-chamber 2 and its delivery-nozzle 22. As in my Letters Patent No. 324,905, the capacity of delivery may be increased or diminished, as required, by open-

ing more or less of the passages 46, or by the substitution of a plug having a greater or less delivery area.

In the instance illustrated the apparatus is 5 suitably adapted to operate in connection with a proportional meter of any preferred construction, an instance of which is set forth in my application, Serial No. 148,191, filed November 17, 1884. To this end a meter-sup-
ply nozzle, 53, having a small central passage, 52, the area of which is any desired fraction of the total delivery area, is connected to the valve-easing 1 on the delivery side of the valve-seat partition 35, and the area of the passages 15 through the plug or partition 45 equals the total delivery area, less the area of said passage. In this case nineteen passages, each equal in area to the passage 52, are formed in the partition 45, and the passage 52 is there-
fore adapted to deliver one-twentieth of the total volume of supply. A meter-delivery nozzle, 54, is formed upon the side of the delivery-passage 22 of the pressure-chamber 2, and a suitable meter may be connected on its 25 receiving and delivery sides, respectively, to the nozzles 53 and 54. The quantity of gas registered by the meter will consequently be one-twentieth of the quantity passing to the service-pipes, and a meter of correspondingly-
30 reduced dimensions will suffice to effect registration.

Longitudinal movement is imparted to the valve-stem 36 to effect the regulation or the entire closure, as the case may be, of the opening through the partition 35 for the passage of fluid from the supply to the delivery pipes by a movable abutment composed of a flexible diaphragm, 15, extending across the pressure-chamber 2 above its supply and delivery 35 passages, and a pair of weights or pressure-plates, 20 47, adapted to exert downward pressure on the diaphragm 15. Said diaphragm is secured at and adjacent to its periphery between a flange, 16, extending around the top of the pressure-chamber 2, and a cap or cover, 17, connected by bolts 18 to the flange, and carries fixed upon its upper side a weight or pressure-plate, 20. The weight 20 is of less diameter than the interior of the chamber 2, 40 and the diaphragm 15 is cupped or dished—that is to say, made sufficiently large to present a free flexible annular surface between its confined upper portion and the periphery of the weight 20, of proper length to admit of the desired degree of vertical traverse of the weight 20 and attached lower portion of the diaphragm. A stem, 29, upon which is fixed a plate, 30, adapted to bear against the lower side of the diaphragm 15, passes freely through 45 the diaphragm and pressure-plate, and carries upon its upper end a head or stop nut, 41, the stem 29 being caused to follow the movements of the diaphragm and pressure-plate within their range under normal pressure by a helical spring, 40, interposed between 50 and bearing against the lower side of the head 41 and the upper side of the weight 20. The

lower end of the stem 29 is coupled to the longer arm of a bell-crank lever, 32, which may be formed of two plates, as shown, the shorter arm 70 of which lever is coupled by a pin, 37, to the end of the stem 36 of the regulating and cut-off valve. The lever 32 is pivoted by a pin, 33, at the junction of its arms to a bearing on the inner face of the delivery check-plug or per- 75 forated partition 45. Under the above construction the downward and upward movements of the diaphragm and weight will, as in my prior patents, effect the opening and the closure of the regulating and cut-off valve, in 80 accordance with and proportionately to variations of pressure in the fluid entering the pressure-chamber 2, and upon the cessation of fluid-supply, or the diminution thereof below the degree sufficient to support combustion 85 at the burners, the movement of the stem 36 to the right, effected by the gravity of the weight 20, will bring the left-hand disk of the valve 34 to its seat and thereby cut off the supply of fluid. 90

In order to provide for the regulation of pressure for both a maximum and a minimum average, a supplemental weight, 47, is fixed upon the lower end of a stem, 48, fitting freely in a guide bushing or socket, 49, in the cap or 95 cover 17 of the pressure-chamber in line axially with the stem 29 of the diaphragm, the supplemental weight 47 having a central recess or chamber, 50, the top of which is adapted to bear on the head 41 of the stem 29. The 100 downward traverse of the supplemental weight is limited to desired degree by a head or stop, 51, on the upper end of the stem 48, which head abuts against the top of the guide-opening of the socket 49, through which the stem 48 105 passes.

In regulating supply of average maximum pressure the flexible diaphragm 15 is raised to such level that the stem 29 is subject to the action of the gravity of both the main and the 110 supplemental weights, as opposed to the upward pressure of fluid upon the diaphragm, and in the event of such deficiency or shortage of supply as to effect a material reduction of pressure the downward pressure of the supplemental weight is relieved as soon as the 115 diaphragm moves downward for a sufficient distance to permit the head or stop 51 of the stem of the supplemental weight to come to a bearing upon the top of its guide-socket. 120 The delivery-pressure being then materially reduced to, say, one-half, the diaphragm continues to effect regulation under the action of the main weight only, for a minimum average pressure, which it maintains until such 125 further reduction of supply-pressure as causes it by its corresponding downward movement to effect the closure of the regulating and cut-off valve, and thereby to wholly cut off supply. 130

For the purpose of admitting of the renewal of the supply of fluid after having been cut off, the regulator is provided with a by-pass valve, 8, adapted to be operated by hand, to admit fluid to the pressure-chamber 2, and re-

lief of excess of pressure in said chamber is provided for by a series of openings, 38, in the diaphragm, which register with corresponding passages, 39, in the main weight 20, and are normally closed to the fluid in the chamber 2 by the plate 30. Said devices accord substantially with those illustrated for similar purposes in Letters Patent No. 324,905 aforesaid, and, not constituting part of my present invention, need not be at length described.

I claim herein as my invention—

1. The combination of a pressure-chamber having supply and delivery passages on its opposite sides, a valve-casing communicating at one end with the supply-passage and at the other with a fluid-supply pipe, a double-beat regulating and cut-off valve controlling an opening in a transverse partition in the valve-casing, and a weighted movable abutment working in the pressure-chamber above its supply and discharge passages and coupled to the stem of the regulating and cut-off valve, these members being combined for joint operation to enable the pressure-chamber to be employed as part of the line of the traverse of fluid from the supply to the delivery pipes, substantially as set forth.

2. The combination of a pressure-chamber having supply and delivery passages on its opposite sides, a valve-casing connected at one end to the supply-passage, and adapted to communicate at the other with a fluid-supply pipe, a perforated delivery check-plug extending across the valve-casing at or near its end next to the pressure-chamber, a double-beat regulating and cut-off valve controlling an opening in a transverse partition in the valve-casing and fixed upon a stem passing freely through the delivery check-plug, and a weighted movable abutment working in the pressure-chamber above its supply and discharge passages and coupled to the stem of the regulating and cut-off valve, substantially as set forth.

3. The combination of a pressure-chamber having supply and delivery passages on its opposite sides, a valve-casing connected at one end to the supply-passage, and adapted to communicate at the other with a fluid-supply pipe, a perforated delivery check plug or partition extending across the valve-casing at or near its end next the pressure-chamber, a double-beat regulating and cut-off valve controlling an opening in a transverse partition in the

valve-casing and fixed upon a stem passing freely through the delivery check-plug, a 55 weighted movable abutment working in the pressure-chamber and coupled to the stem of the valve, a meter-supply nozzle having a passage of determined fractional area relatively to the perforations of the delivery check-plug, 60 which leads out of the valve-casing on the supply side of said plug, and a meter-delivery nozzle communicating with the delivery-passage of the pressure-chamber, substantially as set forth.

4. In a pressure-regulating apparatus, the combination of a regulating-valve, a weighted diaphragm coupled to said valve, and a supplemental weight disconnected from said diaphragm and adapted to exert pressure thereon during only a portion of its entire traverse, substantially as set forth.

5. In a pressure-regulator and cut-off, the combination of a regulating and cut-off valve governing the admission of fluid to a pressure-chamber, a movable abutment working in said chamber and coupled to the stem of said valve, a weight connected to and continuously exerting its gravity upon said abutment, a supplemental weight adapted to bear upon said 80 abutment during a portion of its range of traverse, and a fixed bearing which sustains the supplemental weight and relieves the movable abutment from the pressure thereof during the remainder of the traverse of the abutment, 85 substantially as set forth.

6. The combination of a pressure-chamber, a regulating and cut-off valve working in a casing communicating with said chamber and governing the admission of fluid thereto, a 90 movable abutment working in the pressure-chamber and coupled to the stem of the regulating and cut-off valve, a main weight connected to said abutment, a supplemental weight fixed upon a stem working in a guide in the 95 pressure-chamber above the movable abutment, a head or stop secured to said stem, and a fixed bearing against which said stop abuts to limit the downward traverse of the supplemental weight, substantially as set forth.

In testimony whereof I have hereunto set my hand.
